CLAIM

The ornamental design for an artificial fishing lure, as shown.

DESCRIPTION

FIG. 1 is a right side elevational view of an artificial fishing lure, showing my new design, the opposite being a mirror image thereof;

FIG. 2 is a top plan view thereof;

FIG. 3 is a bottom plan view thereof;

FIG. 4 is a front elevational view thereof; and,

FIG. 5 is a rear elevational view thereof.
